UNITED STATES PATENT OFFICE.

MERRILL PEPPERD, OF WILMORE, KANSAS.

AIRPLANE-STARTER.

1,258,450.

Specification of Letters Patent.

Patented Mar. 5, 1918.

Application filed September 5, 1917. Serial No. 189,826.

To all whom it may concern:

Be it known that I, MERRILL PEPPERD, a citizen of the United States, residing at Wilmore, in the county of Comanche and State of Kansas, have invented new and useful Improvements in Airplane-Starters, of which the following is a specification.

This invention relates to airplane starters, the object in view being to provide means to enable an aviator to turn the propeller and start the engine of his airplane without requiring the assistance of any other person. While the improved device is especially useful in connection with hydroaeroplanes, it will also be found useful on all types of airplanes and also useful in starting all internal combustion engines, the improvement being also designed for use on automobiles.

With the above and other objects in view, the invention consists in the novel construction, combination and arrangement of parts, herein described, illustrated and claimed.

In the accompanying drawings:—

Figure 1 is a diametrical section through the improved airplane starter.

Fig. 2 is a section on the line 2—2 of Fig. 1.

Fig. 3 is a section on the line 3—3 of Fig. 1.

Fig. 4 is a section on the line 4—4 of Fig. 1.

Fig. 5 is a detached view of the combined ball and roller bearing.

Fig. 6 is a detail view of the combination nut.

The improved starter contemplated in this invention comprises a rotary drum 1 which is mounted to turn within a cylindrical housing 3. The housing 3 is non-rotary and is provided with circumferential flanges 4 and 5, the flange 4 being secured by fastening means 5' to a fixed support and frame plate 6 which may in turn be secured to the frame of the vehicle.

Extending centrally through the drum is the propeller shaft 7, 8 designating an aerial propeller secured in fixed relation to the rotatable drum 1 by means hereinafter more particularly described. Fast on the propeller shaft 7 is a plurality of central gears 9.

Meshing with the gears 9 is a plurality of gears 10 arranged in circular formation around the gear 9. In fixed relation to the gears 10, and mounted on the same shafts or hubs therewith are other gears 11 which in turn mesh with another circular series of

gears 12. The gears 12 carry other gears 12' which mesh with an internal gear face 13 on the inside of the drum 1 and therefore when the drum 1 is revolved, motion is transmitted through the gears 9, 10, 11, and 12 to the propeller shaft 7 at an accelerated speed as compared with the speed of rotation of the drum 1. Gear holding spiders or yokes 14 connect the shafts of the several gears 10, 11 and 12 at opposite sides of the trains of gears as shown in Fig. 1 and indicated by dotted lines in Fig. 2. In order to reduce friction to a minimum, anti-friction rollers 15 are interposed between the outer face of the drum 1 and the inner faces of the housing 3. At one end, the rollers 15 abut against a stop flange 16 of the housing 3 and at their other ends they abut against a flange 17 on an oscillatory rim 18. Around the rim 18 is wrapped a flexible connection 19 such as a cable which is attached at one end to the rim 18, said cable passing around a guide pulley 20 journaled in a bracket 21 secured by fastening means 22 to the flange 80 5 of the housing 3. The cable 19 is provided at its free extremity with a suitable handle 23 which the operator pulls in order to rotate the rim 18 and impart rotary motion to the drum 1.

The connecting means between the oscillatory rim 18 and the drum 1, comprises a ratchet face 24 on the drum 1, and a plurality of pawls 25 connected by pivots 26 to the oscillatory rim 18. Any desired number of pawls may be employed and each pawl is arranged in a recess 27 in the rim 18. Located outside of each pawl 25 is a presser head 28 having a convex face 29 against which the cable 19 is adapted to operate for the purpose of pressing the head 28 inwardly and forcing the pawl 25 into engagement with the ratchet face 24. Normally the pawl 25 is held out of engagement with the ratchet face 24 by means of a bowed spring 30 the ends of which rest in the recess 27 and the central part of which is attached at 31 to the adjacent pawl 25. As soon as a pull is effected on the cable 19, it presses inwardly on the heads 28 and throws the pawls 25 into engagement with the ratchet face 24 of the drum 1. As soon as the cable 19 is relaxed, the pawls 25 are moved out of engagement with the ratchet face 24 by the action of the springs 30 and the outward movement of the presser heads 28.

The drum 1 is provided at one side with a

head 32 having a central opening 33. The outer face of the head 33 is rabbeted as shown at 34 to receive a bolt locking plate 35 formed in the periphery thereof with notches 36 to engage and prevent the turning of a corresponding number of propeller fastening bolts 37 each of which has opposite flat sides to fit the respective notch 36 when the locking plate 35 is in place. The plate 35 therefore locks all of the bolts 37. The head 32 is formed with key-hole slots 38 to receive the bolts 37. The bolts are first passed through the larger portions of the slots 38 and then moved radially outward, after which the locking plate 35 is inserted in place. The propeller 8 is then passed over the bolts 37, and the nuts 39 tightened. Thus a firm and reliable mounting for the propeller is obtained in relation to the drum 1.

A bearing plate 40 is mounted within the head 32 of the drum and formed with a flange 41 secured to said head by fastening means 42 such as rivets. The plate 40 has a central opening to receive a combined ball and roller bearing, the latter comprising an annular series of rollers 43 which work within the opening of the plate 40, and also an annular series of balls 44 which work within a cage portion 45 of the combined ball and roller bearing. Said bearing also comprises a cage 46 for the rollers 43; a combined radial and end thrust bearing is thus provided which will reduce the friction of rotation and end thrust to a minimum, this being of great importance so as not to absorb any of the power of the engine by which the propeller is driven. Another radial thrust roller bearing 47 is arranged in an opening in the frame plate 6, surrounding the propeller shaft 7.

The end portion of the propeller shaft 7 is threaded to receive a nut 48 and a lock nut 49 which abuts against the nut 48. The main nut 48 is formed with a series of notches 50 and the lock nut 49 is formed with a corresponding number of bendable tongues 51. The nut 48 bears against a ball bearing washer or collar 52 on the propeller shaft, and the lock nut 49 is secured tightly against the nut 48 and then locked by swaging the tongues 51 into the notches 50.

From the foregoing description taken in connection with the accompanying drawings it will be seen that I have provided an efficient starter for airplane propellers and engines, the construction being such as to reduce friction to a minimum and cause all parts to operate with precision and smoothness and without any liability of binding or cramping and thereby detracting from the highest power efficiency of the engine. The operating cable 19 may extend to any convenient part of the vehicle so that it will be in reach of the operator at any moment.

The drum 1 is returned to its initial point by means of a spring 53 which surrounds the oscillatory rim 18 and is held in place by a guard ring 54. Another guard ring 55 is secured to the oscillatory ring 18 to prevent the cable 19 from slipping therefrom during the operation of the starter.

I claim:

1. In a starter of the class described, the combination of a stationary cylindrical housing, supporting means for said housing, a rotatable drum journaled within said housing, a centrally arranged shaft, an internal gear face within said drum, a train of gears interposed between said internal gear face and said centrally arranged shaft for accelerating the rotation of the shaft in relation to said drum, an oscillatory rim surrounding a portion of said drum, pawl and ratchet means between said rim and drum, and a flexible operating cable surrounding said oscillatory rim and attached thereto.

2. In a starter of the class described, the combination of a stationary cylindrical housing, supporting means for said housing, a rotatable drum journaled within said housing, a centrally arranged shaft, an internal gear face within said drum, a train of gears interposed between said internal gear face and said centrally arranged shaft for accelerating the rotation of the shaft in relation to said drum, an oscillatory rim surrounding a portion of said drum, pawl and ratchet means between said rim and drum, a flexible operating cable surrounding said oscillatory rim and attached thereto, and a return spring for actuating said drum in the opposite direction.

3. In a starter of the class described, the combination of a stationary cylindrical housing, supporting means for said housing, a rotatable drum journaled within said housing, a centrally arranged shaft, an internal gear face within said drum, a train of gears interposed between said internal gear face and said centrally arranged shaft for accelerating the rotation of the shaft in relation to said drum, an oscillatory rim surrounding a portion of said drum, pawl and ratchet means between said rim and drum, a flexible operating cable surrounding said oscillatory rim and attached thereto, said pawl and ratchet means comprising a ratchet face on the drum, a pawl adapted to operate therewith and pivotally carried by said oscillatory rim, yieldable means normally holding said pawl out of engagement, and means operated upon by said cable serving to press the pawl into engagement with the ratchet face.

4. In a starter of the class described, the combination of a stationary cylindrical housing, supporting means for said housing, a rotatable drum journaled within said housing, a centrally arranged shaft, an internal

gear face within said drum, a train of gears interposed between said internal gear face and said centrally arranged shaft for accelerating the rotation of the shaft in relation to said drum, an oscillatory rim surrounding a portion of said drum, pawl and ratchet means between said rim and drum, a flexible operating cable surrounding said oscillatory rim and attached thereto, said pawl and ratchet means comprising a ratchet 10 face of the drum, a pawl adapted to co-

operate therewith and pivotally carried by said oscillatory rim, yieldable means normally holding said pawl out of engagement, and means operated upon by said cable serving to press the pawl into engagement with the ratchet face, said yieldable means also serving to press the last named means outwardly to permit the pawl to move out of engagement with the ratchet face. 15

In testimony whereof I affix my signature.

MERRILL PEPPERD.
